(57) **CLAIM**

The ornamental design for a safety box for pistol, as shown and described.

DESCRIPTION

FIG. 1 is a perspective view of a safety box for pistol showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged portion view taken from encircled labeled, "FIG. 9", in FIG. 1; and,

FIG. 10 is an enlarged portion view taken from encircled portion labeled, "FIG. 10", in FIG. 3.

The dash-dash broken lines in the drawings are for the purpose of illustrating portions of the safety box for pistol that form no part of the claimed design. The dot-dash broken lines represent boundaries of the enlarged portions and form no part of the claimed design.
